United States Patent Office

Des. 185,676
Patented July 14, 1959

185,676

COMBINED SOFA BED, DESK, AND DRESSER

John Maguire, Los Angeles, Calif., assignor to Duo-Bed Corporation, Los Angeles, Calif., a corporation of Nevada

Application January 26, 1959, Serial No. 54,323

Term of patent 14 years

(Cl. D15—11)

Fig. 1.

Fig. 2.

Fig. 3.

Fig. 1 is a perspective view showing a combined sofa bed, desk and dresser embodying my new design with the sofa bed and bolster in closed position;

Fig. 2 is a perspective view of the same with the sofa bed and bolster in open position;

Fig. 3 is a top plan view of the same with the sofa bed and bolster in closed position.

I claim:

The ornamental design for a combined sofa bed, desk and dresser substantially as shown.
